UNITED STATES PATENT OFFICE.

AUGUSTUS M. SOSA, OF CINCINNATI, OHIO, ASSIGNOR TO THE AMERICAN TOOL WORKS COMPANY, OF CINCINNATI, OHIO, A CORPORATION OF OHIO.

FEEDING MECHANISM FOR METAL-WORKING MACHINERY.

1,375,024.

Specification of Letters Patent. Patented Apr. 19, 1921.

Application filed September 10, 1917. Serial No. 190,655.

To all whom it may concern:

Be it known that I, AUGUSTUS M. Sosa, a citizen of the United States, residing at Cincinnati, in the county of Hamilton and State of Ohio, have invented certain new and useful Improvements in Feeding Mechanism for Metal-Working Machinery, of which the following is a specification.

I have exemplified my invention as embodied in a drilling machine comprising a laterally extending supporting arm having a tool-slide guidable laterally thereon and an axially movable tool-spindle for supporting the cutting tool.

My invention relates to feeding mechanism for metal working machinery, especially to the means for counterweighting the tool-spindle.

It is the object of my invention to provide a novel arrangement of counterweighting mechanism located at the same side of the tool-arm at which the tool-slide has its guiding connection with the tool-arm and embodying a flexible connection between the counterweight and the tool-spindle, whereby the weight of the tool-spindle and counterweight are located at the same side of the tool-arm, for relieving those guiding faces between the tool-slide and tool-arm which receive the end-thrust of the tool, from the stress of the weight of the spindle and counterweight.

It is a further object of my invention to provide novel means for arresting descent of the counterweight upon accidental disconnection of the counterweight from the tool-spindle.

The invention will be further readily understood from the following description and 40 claims, and from the drawings, in which latter:

Figure 1 is a front elevation of the tool-slide and a portion of the drill-arm of a drilling machine, embodying my invention, 45 the front portion of the casing of the tool-slide being partly broken away.

Fig. 2 is a side elevation of the same, with part of the casing broken away, and partly in vertical section in the plane of the line 50 2-2 of Fig. 1, with the tool-spindle shown at its upward limit of axial movement.

Fig. 3 is a fragmentary horizontal section of the front portion of the tool-slide, taken in the plane of the line 3-3 of Fig. 1.

Fig. 4 is a vertical section showing the

mounting of the drill-spindle, taken in the plane of the line 4-4 of Fig. 3.

Fig. 5 is a horizontal section of the front portion of the tool-slide, taken in the plane of the line 5-5 of Fig. 1.

Fig. 6 is an enlarged detail section of the counter-weight and its rod, taken in the plane of the line 6-6 of Fig. 4; and,

Fig. 7 is a detail cross-section of the counter-weight and its rod, taken in the plane of the line 7-7 of Fig. 6.

The tool-slide of the drilling machine, which is exemplified as embodying my invention, is represented at 11. It is instanced as supported by a supporting arm 12, exemplified as a drill-arm, on which it is laterally adjustable. The drill-arm is provided with a guide 13 extending lengthwise thereof.

The lower part of this guide comprises a rearwardly and upwardly extending inclined face 14 which, with the forward face 15 of the guide, coacts with an inclined face 16 and a rear face 17 in the tool-slide. The upper portion of the guide comprises an upper face 18 extending at substantial right angles to the forward guiding face 19, and a rear guiding face 20, respectively coacting with the horizontal face 21, the rear face 22 and the forward faces of guide-strips 24, the latter secured by bolts 25 to the tool-slide at suitable intervals lengthwise of the guide on the tool-slide. The inclined guide-faces 14 and 16 receive the upward thrust of the tool, exemplified as a drill 26, in the tool-spindle 27, exemplified as a drill-spindle. It is desirable to relieve these inclined faces of other duty and to prevent wedging action on said faces.

The lateral adjustment of the tool-slide may be accomplished by providing the supporting arm with a rack 31, with which a pinion 32 is arranged to mesh in usual manner, the pinion being operated in suitable manner, as by a hand-wheel 33 on a shaft 34, journaled in bearings 35 on the tool-slide, and having a worm 36 fast thereon. The worm meshes with a worm-wheel 37 fast on a shaft 38, the shaft having a gear 39 fast thereon which meshes with the pinion 32.

The drill-spindle 27 is mounted on the tool-slide in usual manner, and usual means are provided for rotatively driving and for feeding the same. Thus a shaft 41 extends

lengthwise of the supporting arm, being driven in suitable manner at selective speeds from the column of the drilling machine by usual means, not shown because well-known. The shaft has a sleeve 42 thereabout, said sleeve movable with the drill-head and having spline-connection 43 with the shaft. A pair of opposed bevel-gears 44, 45, are normally loose about the sleeve 10 and are arranged to be selectively secured thereto by usual clutch means operated by an operating arm 46. A bevel-gear 47 is meshed at its opposite sides by said last-named pair of bevel-gears for driving the 15 bevel-gear 47 in opposite directions.

Bevel-gear 47 has a gear 48 fast therewith, which meshes with a gear 49 fast on a shaft 50 journaled in a bearing 51 of the tool-slide and having a gear 52 fast thereon. 20 The gear 52 meshes with a gear 53 fast with a bushing 54 journaled in a bearing 55 of the tool-slide. The gear 53 has spline-connection 56 with the drill-spindle for permitting axial movement of the drill-spindle 25 in the gear and retaining driving connection between the gear and drill-spindle throughout said axial movements.

The drill-spindle rotates in a sleeve 61, between which and the spindle there are 30 end-abutment bearings 62, 63, for causing axial movement of the spindle with the sleeve. The sleeve slides axially in a bearing 64 on the tool-slide. It is provided with a key 65 guided lengthwise in a slot 66 in 35 said bearing. The sleeve is provided with a rack 69 with which a pinion 70 engages, the pinion being fast on a shaft 71 which is received in a bushing 72 of a face-plate 73, a key 74 securing said shaft and bushing 40 together. A worm-wheel 76 is provided with a bushing 77 in which the bushing 72 is arranged to rotate, the bushing 77 being rotatable in a bearing 78 in the tool-slide. The pinion 70 is arranged to be rotated, 45 either by means of said worm-wheel, or by means of handles 79 extending from said face-plate. A clamp 80 is arranged to clamp the face-plate to the worm-wheel, the face-plate having an annular bearing 81 about 50 said worm-wheel.

The worm-wheel is arranged to be operated by a worm 86 which meshes therewith and is fast on a shaft 87 journaled in a bearing 88 of the tool-slide and having a hand-wheel 89 for manually operating the same. The worm 86 may also be rotated by a shaft 91, the lower end of which is received journalwise in a bore 92 in said worm. 55

The shaft 91 is journaled in a bearing 94. 60 A clutch 95 is arranged to operatively connect the shaft 91 with the worm, the teeth of the clutch being respectively on the hub of said worm and on a collar 96, having spline-connection 97 with the shaft 91. The 65 collar is arranged to be moved lengthwise

of the shaft, for connecting or releasing said clutch, by means of a fork 98, the tines of which are received in an annular groove 99 in said collar, the fork being actuated by a handle 100.

The shaft 91 is arranged to be rotated, preferably at selective speeds, as by means of coaxing nests of gears of various diameters, exemplified at 101, the speeds of which are controlled by an index-wheel 102, in any 75 well-known manner, and which are operated by means of a gear 103 fast with the gear 53 about the drill-spindle, the gear 103 meshing with a gear 104 arranged to drive the gears of the nests of gears. 80

Feeding or axial movements may be imparted to the tool-spindle manually by means of the handles 79, for causing quick raising and lowering of the tool-spindle, or the feeding movements may be imparted 85 to the tool-spindle manually by means of the hand-wheel 89, or by means of the power-driven gearing through the medium of the clutch 95.

The counterweighting mechanism for the 90 tool-spindle is exemplified as comprising a weight 106, slideable on a guide-rod 107. The guide-rod is connected at its lower end with the tool-slide, as by a screw 108. The guide-rod is, at its upper end, received 95 through a thimble 109 in an aperture 110 in a cross-web 111 of the casing 112 of the tool-slide, a nut 113 about the threaded end of the guide-rod clamping the guide-rod in place in stretched relation. The guide-rod 100 is parallel with the drill-spindle and adjacent thereto, for locating the counterweight and the drill-spindle at the same side of the drill-arm. Suitable parts of the casing are made removable for insertion of the working parts. 105

The counterweight is connected with the drill-spindle by a flexible connection 115, which extends upwardly from its connection with the counterweight over a suitable pulley 116 on a shaft 117 journaled in bearings 118 of the cross-web 111, and extending thence downwardly and having connection at 119 with a bracket 120 fixed to the axially movable sleeve 61 about the drill-spindle. 115

By this arrangement of the counterweighting means for the drill-spindle, the downward stress upon the tool-slide, due to the weight of the drill-spindle and the counterbalance weight, is exerted along adjacent 120 parallel lines forward of the guide on the supporting arm for the tool-slide. As a result, the weight of the tool-slide is so balanced upon said supporting arm as to avoid any tendency of the slide to tilt rearwardly 125 upon the supporting arm, which is the case when the counterweight is positioned in rear of the supporting arm, which latter arrangement has a tendency to cause the tool-slide to tilt on the supporting arm, employing the 130

corner between the faces 18 and 19 as a fulcrum, and drawing the lower inclined face 16 of the tool-slide outwardly into wedging engagement with the coaxing inclined face 14 of the guide, so as to cause a binding stress between the tool-slide and its supporting arm, which prevents ready lateral adjustment of the tool-slide.

The detrimental effects of such an arrangement are avoided in my device, in which the weight of the drill-spindle and counterweight are exerted upon the tool-slide in parallel lines forwardly of the guide therefor on the supporting arm, being connected by the flexible connection, whereby the stress of the weight of the tool-slide and the parts supported thereby are received in downward direction between the guide-faces 18, 21, the tool-slide further being supported by the front and rear upper guiding faces of the guide and guideway between the supporting arm and tool-slide, to avoid tilting of the tool-slide, and tending to relieve pressure between the inclined faces 14 and 16 for providing ease of lateral adjustment and preventing tilting and wear of the parts, and thereby insuring accuracy in the position of the drill, the upward thrust of which is received by the faces 14 and 16.

The counterweight is provided with a safety latch arranged to prevent dropping thereof upon accidental disconnection of the counterweight from the drill-spindle, as may be caused, for example, by breakage of the flexible connection between them.

For this purpose a bore 121 extends through the counterweight, forming a slideway through which the guide-rod 107 extends. The counterweight is provided with a recess 122 at the side of the slideway. A latch 123 is received in this recess and is pivoted to the counterweight on a pin 124. The latch is provided with a tooth 125 which is arranged to selectively engage the teeth of a rack 126 on the guide-rod upon failure of the normal supporting means for the counterweight. The latch is provided with an arm 127 at the side of the pivot-pin 124 opposite the latching tooth thereon.

The flexible connection from the drill-spindle is connected to the operating arm of the latch, preferably by having a ring 128 thereon received over a hook 129 pivoted to the operating arm of the latch by a pin 130. The normal upward pull exerted by the flexible connection upon the operating arm is such as to normally cause disengagement of the tooth of the latch from the teeth on the guide-rod.

Upon failure of the flexible connection to support the counterweight, the tooth of the latch is arranged to be forced into engagement with that portion of the rack adjacent to the latch at the time of such failure.

This is exemplified as effected by a yieldable plunger 131 acting on the heel 132 of the latch, preferably at that side of the pivot of the latch opposite the tooth thereon, so that the tooth of the latch is forced into engagement with an adjacent tooth on the guide-rod. The plunger is received in a bore 134 in the counterweight, and is yieldingly urged toward the latch by a spring 135 received about the shank 136 of the plunger between a shoulder 137 on said plunger and a plug 138 threaded into the outer end of said bore. (See Fig. 6.)

The operating arm of the latch is provided with a contact-face 139 arranged to abut a contact-face 140 on the wall of the recess 122 in the counterweight, when the tooth of the latch has been moved into meshing engagement with the rack, for preventing swinging movement of the latch beyond its operative latching position and avoiding a shearing force on its pivot. When the latch 123 has thus engaged the rack, it will prevent descent of the counterweight, thus avoiding the dropping of the counterweight and consequent jarring of the tool-slide or parts thereof, or of the machine, and avoiding injury to the operator by reason of falling of the counterweight.

The tool-slide comprises a casing 112 which surrounds the spindle and incloses the driving means and feeding means for the spindle mounted on the tool-slide, as well as the counterweight mechanism on the tool-slide, forming a compact structure wherein the parts mentioned are contained, and forming a self-contained structure.

The counterweight comprises a skeleton 146 in which the recess and bore for receiving the latch and plunger therefor are contained, and having therein the bore through which the supporting rack extends. This skeleton supports the operating parts of the arresting means for the counterweight mechanism. It is, for instance, a casting of usual gray iron, and is provided with off-set faces 147, 148, and 149, and with a projection 150 having a rib 151 thereon. A body 152 of heavier metal, for instance, lead, is cast about said projection for securing the same to said skeleton, said weighting body depending from said skeleton. The weighting body has a portion of the bore 121 therethrough. My improved construction provides ready means whereby a heavy counterweight for the spindle is provided, which occupies small space and enhances the compactness of the tool-slide and the structures mounted thereon.

My improved device further provides means whereby the counterweight is inclosed in a strong closed casing, so that, even if there were failure of the latch to stop the accidental dropping of the counter-

weight, the counterweight could not drop off the tool-head, but would be retained in the casing.

Having thus fully described my invention, 5 what I claim as new and desire to secure by Letters Patent, is:

1. In a metal working machine, the combination of a tool-slide, an axially feedable tool-spindle journaled thereon, a counterweight 10 movable in a line substantially parallel with the line of feeding movement of said tool-spindle, a rack for said counterweight substantially parallel with the line of movement of said counterweight, a latch 15 pivoted to said counterweight, means to urge engagement of said latch with said rack, and a supporting connection for said counterweight extending upwardly directly from said latch to exert a pull 20 on said latch in a line substantially parallel with said line of movement of said counterweight, said supporting connection having supporting connection with said tool-spindle.
2. In a drilling machine, the combination 25 with the axially feedable drill-spindle, of counterweighting means therefor comprising a counterweight movable in a line substantially parallel with the line of feeding 30 movement of said drill spindle, a coacting rack therefor, a latch pivoted to said counterweight and provided with a tooth for engagement with the teeth of said rack, a resilient part acting on said latch to urge 35 said tooth into engagement with said rack, the pivot of said latch being located between said resilient part and said rack, and

a tension-member supporting said weight having connection with said latch at the same side of its pivot as the side with which 40 said resilient part coacts and extending directly upward from said latch to exert a pull on said latch in a line substantially parallel with the line of movement of said counterweight.

3. In a drilling machine, the combination with the axially feedable drill-spindle, of a counterweight therefor, said counterweight having a bore therethrough, a rack received through said bore, said axially 50 feedable drill-spindle, said bore and said rack being substantially parallel, a spring-pressed plunger, a latch having a pivot on said counterweight, said latch provided below its pivot with a tooth for engagement with said rack, a heel arranged to be pressed by said spring-pressed plunger to urge engagement of said latch with said rack, and a heel arranged to engage said counterweight to prevent overthrow of said latch with relation to said rack, and a tension-member 55 having connection with said latch and extending directly from said latch in a direction substantially parallel with said rack to exert direct pull on said latch in line with the line of movement of said counterweight.

In testimony whereof, I have hereunto signed my name in the presence of two subscribing witnesses.

AUGUSTUS M. SOSA.
